SPRING BUMPER AND DRAFT GEAR

Fred J. Bogard, Huntington, W. Va., assignor to ACF Industries, Incorporated, a corporation of New Jersey

Application November 3, 1950, Serial No. 193,796

5 Claims. (Cl. 213—9)

This invention relates to spring bumpers and draft gears in general and in particular to such gears intended for use on mine or other industrial cars.

In mine and industrial work it is generally necessary to provide high capacity buff and draft gears yet keep the space requirements to a minimum. It is further desirable that the resistance of the gear to draft forces should be half or less or the resistance to buffing forces. It is an object, therefore, of the present invention to provide a combined spring bumper and draft gear having the spring means so arranged as to give substantially less draft than buff resistance.

A further object of the invention is the provision of a combined spring bumper and draft gear having a plurality of resilient means acting in unison to resist buffing forces, while some only act to resist draft forces.

A still further object of the invention is the provision of a spring bumper and draft gear having a plurality of resilient devices, certain of which urge the bumper toward the car, while others urge the bumper away from the car.

A yet further object of the invention is the provision of a combined spring bumper and draft gear utilizing concentrically arranged inner and outer coil springs, with the inner springs resisting draft forces as well as buffing forces and the outer springs resisting only buffing forces but being precompressed so as to hold the bumper in position and prevent its rattling.

These and other objects of the invention will be apparent to persons skilled in the art from a study of the following description and accompanying drawings, in which

Fig. 1 is a plan view with portions broken away to better disclose the construction;

Fig. 2 is a sectional view taken substantially on line 2—2 of Fig. 1, and

Fig. 3 is a sectional view similar to the lower half of Fig. 1 but showing the parts when extended under draft forces.

Referring now to the drawings in detail it will be seen that the end portion only of the car structure has been disclosed as formed with side pieces 2 adapted to be attached to the car side sills and joined by a distorted Z-shaped plate 4 to which the car floor may be attached and an angle shaped plate 6 joined to the side pieces and to the upper portion of the distorted Z-shaped plate 4. The uppermost and outwardly directed flange 8 of the distorted Z-shaped plate and the outwardly directed lower flange 10 of the angle member 6 are joined intermediate their ends by vertical plates 12, which plates are in turn joined to each other and to the vertical flange 6 by a horizontal plate 14. The space inclosed by vertical plates 12 and horizontal plates 10 and 14 constitute a housing for the bumper head B.

The bumper head B is preferably constructed with an upper horizontal plate 16 and a lower horizontal plate 18 having their front edges curved and welded or otherwise secured to a heavy buffing plate 20. The rear edges

2

of plates 16 and 18 are welded or otherwise secured to a vertically extending plate 22, thus forming in effect an open ended box shaped bumper head which is movable within the end structure of the car.

5 The vertical plate 6 is pierced at spaced points to slidably receive the shanks of bolts or other means 24 which extend outwardly from the end wall 6 and have a headed end portion 26. This head is adapted to have bearing engagement against the outer end of an inner coil spring 28, the inner end of which bears against a follower 30. This follower 30 is normally held in spaced relation to the end wall 6 by a stop means 32. In the present instance the stop means is of circular cross-section with an external diameter sufficient to pass through a circular opening 34 cut or otherwise formed in the vertical wall 22 of the bumper head. The stop is also provided with an opening through which the shank of bolt 24 may slidably move. As clearly shown the bolt is held in position by a nut or other means 36. Outer coil spring 38 are arranged concentric with the inner springs and have their inner ends bearing against the followers 30, while their outer ends bear against spring seats 40 welded or otherwise secured to and made a part of the bumper head. In order to apply draft forces to the bumper head a 10 shaped member 42 is secured to the bumper head intermediate the spring seats 40 and is provided with a back face 44 adapted to have bearing engagement with a draft pin 46 extending downwardly through openings in the plate 16. As shown the plate 14 is notched sufficiently to permit movement of the pin 46, while the flange 8 of plate 4 is provided with an opening 48 through which the pin may pass. As clearly shown, the pin has the upper portion reduced slightly in diameter as at 50 so that the pin will not tend to move upwardly when being subjected 15 to draft forces.

From the preceding it will be obvious that the inner springs 28 react on the bolt heads to hold the followers 30 against the stops 32 and since the followers 30 bear against the back plate 22 these inner springs 28 resiliently act to urge the bumper head inwardly toward the car structure with the inward motion limited by the stops 32. Any degree of precompression on inner springs 28 may be obtained through adjustment of nut or other means 36. The outer coil springs 38 have their inner ends bearing against the followers 30 and their outer ends bearing against the spring seats 40 of the bumper head; accordingly, these springs tend to urge the bumper head outwardly away from the car and will be sufficiently precompressed at time of assembly as to prevent looseness and rattling of the bumper head.

When the bumper head B is subjected to buffing forces the entire structure moves inwardly toward the car, but since followers 30 are held by stops 32, such inward motion will be resisted by both the inner and outer coil springs being compressed. When draft forces are applied to the pin 46 this pin tends to pivot around the edge of the hole in plate 8, causing the lower end to move outwardly, thereby moving the entire bumper head outwardly. Outward movement of the bumper head is resisted only by the inner coil springs 28 as clearly shown in Fig. 3. In other words, the coil springs 38 do not undergo any change in draft forces but are bodily carried outwardly with the bumper head; this being due to the fact that the followers 30 bear directly against the back plate 22.

While the construction has been described more or less in detail with specific reference to the drawings it will be obvious that various modifications and rearrangements of parts may be made without departing from the scope of the claims defining my invention.

What is claimed is:

1. In a combined draft and buffing gear for cars, the

combination with the car of a bumper head movable outwardly and inwardly relative to the car under draft and buffing forces respectively from a normal position, spaced apart pairs of coil springs interposed between the car structure and bumper head and each pair comprising concentrically arranged inner and outer coil springs with the outer ends of the outer coil springs bearing on the bumper head, means carried by the car structure and bearing against the outer ends of the inner springs of each pair, follower plates interposed between the inner ends of both the inner and outer coil springs of each pair and a portion of the bumper head, and stop means limiting the motion of said follower plates toward the car structure.

15

25
In addition of said follower plates toward the car structure.
2. In a combined draft and buffing gear for cars, the combination with the car of a bumper head movable outwardly and inwardly relative to the car under draft and buffing forces respectively from a normal position, a plurality of coil springs resiliently resisting the movement of the bumper head, a follower movable outwardly with the bumper head and having bearing engagement with the inner ends of said coil springs, means limiting the movement of said follower inwardly toward the car structure, and means carried by the car structure and bearing against the outer ends of certain of said coil springs, the remainder of said coil springs having bearing engagement at their outer ends upon said bumper head.

3. In a combined draft and buffing gear for cars, the combination with the car of a bumper head movable outwardly and inwardly relative to the car under draft and buffing forces respectively from a normal position, a pair of coil springs resiliently resisting the movements of the bumper head, a follower normally bearing against a portion of the bumper and movable outwardly with the bumper head, means carried by the car structure and extending forwardly into said bumper head, one of said coil springs bearing at one end upon said follower and at the other end upon said bumper head and movable without change outwardly with said bumper head, the other of said

coil springs bearing at one end upon said follower and at the other end upon said means and being compressed during both inward and outward movement of the bumper head, and means limiting the inward movement of said follower toward the car structure.

- 5 follower toward the car structure.
  4. In a combined draft and buffing gear for cars, the combination with the car of a bumper head movable outwardly and inwardly relative to the car under draft and buffing forces respectively from a normal position, stop means, a follower normally bearing against said stop means, securing means carried by said car structure adjacent said stop and follower and projecting forwardly into said bumper head, a first resilient means bearing on said follower and securing means and cooperating with the latter to resiliently hold said follower in bearing engagement with said stop means, and a second resilient means bearing on said bumper head and follower and cooperating with the latter to resiliently urge said bumper head outwardly away from the follower, said bumper head including a portion engaging said follower to limit said outward movement.
- 10
- 15
- 20

5. In a combined draft and buffing gear for cars, the combination with the car of a bumper head movable outwardly and inwardly relative to the car under draft and buffing forces respectively from a normal position, a first resilient means resiliently urging said bumper head inwardly toward the car, a second resilient means bearing on and resiliently urging said bumper head outwardly away from the car, and means limiting the movement of said head inwardly and outwardly under the resilient urging of said resilient means.
